UNITED STATES PATENT OFFICE.

JOHN F. MANSURE, OF PHILADELPHIA, PENNSYLVANIA, ASSIGNOR OF ONE-HALF TO
FRANK P. BROOKE, OF PHILADELPHIA, PENNSYLVANIA.

NECKTIE.

1,238,421.

Specification of Letters Patent. Patented Aug. 28, 1917.

Application filed March 14, 1916. Serial No. 84,001.

To all whom it may concern:

Be it known that I, JOHN F. MANSURE, a citizen of the United States, residing in the city and county of Philadelphia, State of Pennsylvania, have invented certain new and useful Improvements in Neckties, of which the following is a specification.

My invention relates to improvements in neck-ties of the bow-tie type.

10 It has for its object broadly to provide a construction in which one end of the tie is adapted to be bent and looped and so held that it presents an appearance substantially identical with that of the ordinary bow-knot 15 of the bow-tie now in general use.

A further object of my invention is to provide a tie of the character in question having at one end an attaching means for securing the same at the front of the neck 20 band of a shirt and also having a transverse loop at such end. The said tie is also provided with attaching means situated at a point distant from the opposite end of the said tie the portion thereof beyond said last- 25 mentioned attaching means being adapted to be passed through the said transverse loop and then bent upon itself and the end extended reversely through said loop.

30 A further and broadly stated object of my invention is to provide a construction whereby the necessity for tying the same in a bow-knot is obviated.

Other objects and advantages of my invention will be referred to and pointed out 35 in the detailed description thereof which follows or will be apparent from such description.

In the accompanying drawing to which reference should be had for the purpose of 40 more easily understanding my invention I have illustrated one form of a convenient embodiment of the same but it will be understood that the same is susceptible of embodiment in other forms of construction 45 within the scope of the claim appended hereto.

In the drawing:—

Figure 1 is a front elevation of the upper portion of a shirt and a collar and a necktie, the latter embodying my invention;

50 Fig. 2 is a view in elevation of the inside of the tie in extended or flattened position;

Fig. 3 is a longitudinal sectional view of the overlapped ends of a collar and of the 55 front or bow portion of the tie, the over-

lapped ends of both the collar and the necktie being secured together by means of the collar button shown in position; and

Fig. 4 is a perspective view of the front portion of the tie as it appears when tied 60 and when being worn.

Referring to the drawings, 1 designates the upper portion of a shirt and 2 a standing collar of known construction. 3 designates a collar button at the center of the 65 rear of the neck band of the shirt, and 4 the collar button by means of which the front open edge of the neck band of the shirt are connected together and by means of which the front end portions of the tie 70 are connected with the collar and with the neck band of the shirt. 5 designates as a whole a neck-tie embodying my invention which is provided at the center of the portion which extends around the collar with 75 a button-hole 6 which is adapted to be engaged by the outer head (not shown) of the collar button 3. At one end the neck-tie 5 is provided with a button hole 7 adapted to be engaged by the front collar button 4 and 80 is also provided with the loop 8 which extends over or overlies the front side of the end portion of the tie, concealing the button-hole 8. At a point a distance from the opposite end of the tie a button-hole 10 is 85 provided which also is adapted to be engaged by the button 4. The portions of the tie 11 beyond the button-hole 10 are widened and constitute that part thereof which is looped underneath the transversely looped 90 portion 8 for the purpose of forming the bow part of the tie. The tie so arranged is clearly shown in Figs. 1, 3 and 4.

Instead of using the button-holes 6, 7 and 10 any other suitable means may be provided for securing the tie in proper position 95 around the collar.

In placing the tie about the collar and in forming the bow which is shown very clearly in Figs. 1 and 4 of the drawings the collar 100 buttons 3 and 4 are engaged with the button-holes 6 and 7, either being buttoned first as may be desired, after which the end portion 11 extending beyond the button-hole 10 is inserted through the loop 8 and the collar button 4 engaged with the said button-hole 10. 105 It might be that the collar button would or could be engaged with the button-hole 10 before the insertion of the end portion 11 through the loop 8 but usually it is believed 110

that the said portion 11 would be inserted through the transversely extending loop 8 before engaging the collar button 4 with the said button-hole 10. After having inserted 5 the end portion 11 of the tie through the loop 8 and after having inserted the button 4 into the button-hole 10 the end portion 11 is bent forwardly upon itself and extended in reverse direction back through the 10 said loop 8 as is very clearly shown in Figs. 3 and 4 of the drawing to form a loop 12 thereby presenting an appearance substantially identical with that of the bow of the ordinary bow type.

15 It will be seen, therefore, that I have provided a construction of bow-tie which has a single end only which is adapted to be bent and looped to form the bow. While it is true that in such a construction of tie 20 only one end thereof is visible after the same has been placed about the collar and properly looped or folded, yet in actual use this is not noticeable and even if noticed is not objectionable. Such a construction, 25 however, is very advantageous in that it renders the tie easily and readily applicable to the collar so that a person who is unable to tie the usual bow-knot of a tie of this character may with ease and with facility 30 place this tie in position about the collar

and form the loop therein to represent the ordinary bow of a bow-tie as is shown in Figs. 1, 3 and 4 of the drawing.

I claim:—

A bow neck-tie consisting of a band of suitable fabric one end portion only of which is adapted to form the bow of the tie, the said band having a button-hole adjacent the end opposite the said end portion which button-hole is adapted to be engaged by a collar button at the front of the neck band of a shirt, and a loop overlying the front side of the said opposite end including the said button-hole and the said band also having a button-hole at a distance from either end and beyond which the said end portion extends which last mentioned button-hole is also adapted to be engaged by the said collar button, the said first named end portion which extends beyond the last mentioned button-hole being adapted to be extended through the said loop and to be then bent toward the front and extended in reverse direction through the said loop to form the bow of the tie, substantially as described.

In testimony that I claim the foregoing as my invention I have hereunto signed my name this 13th day of March, A. D. 1916.

JOHN F. MANSURE.
